UNITED STATES PATENT OFFICE.

GUSTAVE RICHTER, OF NEW YORK, N. Y.

WINDOW-SHADE HANGER.

1,105,698.

Specification of Letters Patent.

Patented Aug. 4, 1914.

Application filed December 30, 1913. Serial No. 809,537.

To all whom it may concern:

Be it known that I, GUSTAVE RICHTER, a citizen of the United States, residing in the city, county, and State of New York, have invented certain new and useful Improvements in Window-Shade Hangers, of which the following is a specification.

My invention relates to shade hangers of the class in which the shade rollers are made vertically adjustable in order that they may be held close to the top of the window frame or may be lowered to any desired extent for the purpose of admitting light or air over the tops of the window shades when desired.

Many window frames vary in width, being considerably wider in their lower portion than in their upper portion, and the object of my invention is to provide means for supporting shade rollers which are automatically adjustable to accommodate these variations in the width of the window frame in order that the rollers may be firmly held at all times and yet may be raised and lowered with facility.

In carrying out my invention I provide the window frame with vertically arranged guides in which shade brackets of improved construction are adapted to slide, and these brackets are operated by cords or wires guided by suitable pulleys. The brackets are provided with means which allow them to yield or adjust themselves to the varying width of the window frame and may be made of strips of sheet metal with parts that yield automatically for the purpose mentioned.

In the accompanying drawings: Figure 1 shows a window frame (with parts broken away) with my improvements applied. Fig. 2 is a detail view in perspective on an enlarged scale showing one of the brackets and the manner in which it supports the rollers and also how it is guided. Fig. 3 is a detail view in perspective and on an enlarged scale of one of the brackets and its guides. Fig. 4 is a perspective view of a modified form of bracket. Fig. 5 is a perspective view of another modification. Fig. 6 is a perspective view of another form which may be given to the bracket. Figs. 7 and 8 are perspective views showing further modifications. Fig. 9 is a detail view illustrating how shade rollers may be supported by brackets of the kind shown in Figs. 1, 2, and 3.

The window frame A, as shown, is of

usual construction, but my improvements may be applied to window frames of various kinds. I have shown two shade rollers B, B' mounted in the window frame one of which may carry a dark or opaque and the other a light or translucent shade, and I have shown in Fig. 1 brackets C adapted to support both shade rollers. These brackets are received by the vertically arranged guides D which are attached to opposite sides of the window frame and are preferably of the kind shown in Fig. 3 and may extend from top to bottom of the frame or may extend only partway from the top toward the bottom. The brackets C are adapted to support the two shade rollers B, B' and as indicated each bracket is made of sheet metal.

Various kinds of brackets are shown, but those illustrated in Figs. 1, 2 and 3 will first be described. In this case each bracket comprises a part C' adapted to slide in a guide D and a part C² which supports the rollers. The part C' is preferably made of three separate pieces, c, c', c². These three parts are riveted together and overlap each other, as indicated, the upper ends of the parts c and c' being free, as indicated, and to the upper ends of said parts c, c' are attached the horizontal arms c³, c⁴ of the shade supporters. These arms c³, c⁴ are bent at c⁵ where they are attached to the parts c and c' and they are also formed with arches c⁶ which are perforated at c⁷ as indicated. The outer ends of the arms c³, c⁴ are connected by a vertical strip c⁸. By this construction a bracket or support for the rollers of sufficient strength is obtained but which possesses yielding characteristics which will enable the bracket to automatically adjust itself to variations in width of the window frame. The bracket carries anti-friction rollers E which enable it to move up and down easily in the guide D. Two such brackets are employed for each window and these are arranged in the manner clearly indicated in Figs. 1 and 3. In order to raise and lower the shade rollers I may employ any suitable devices but preferably I employ a cord F attached to one of the brackets as indicated at f passed over pulleys G and H and then down to a fastening device I. Another cord may be attached to the other bracket at f' and may be operated by the same cord F. By these devices the shade rollers and the shades may be elevated and

lowered to any desired extent and held in their adjusted positions, the yielding brackets accommodating variations in the width of the window frame.

5 A bracket of simpler construction is shown in Fig. 4 where a single vertical piece J is employed which is adapted to move in a guide D. This piece may carry anti-friction rollers j and may be provided with 10 an eye j' to which the elevating and lowering cord F may be applied. The horizontally arranged arms K are similar to those shown in Fig. 3 and they are connected at their outer ends by a vertical piece K'. 15 These arms are connected at j' to the flat face of the vertical piece J. Two such brackets may be employed, one on each side of the window frame, each bracket serving to support one end of each of two rollers. 20 The guides for the brackets of the kind shown in Fig. 4 should be attached to the outer faces of the window frame so as to hold the rollers away from the frame. In such case the brackets need not possess yielding characteristics inasmuch as there is no variation in the width of the window frame to be regarded.

In Fig. 5 I have illustrated a further modification in which the bracket is made to support only one roller. In this case I employ 30 a vertical part L carrying anti-friction rollers l to which is riveted a part L', somewhat shorter than the part L and attached to it about midway between its upper and lower ends. The part L is bent at l', as indicated, so that its upper portion may stand away from the part L'. To the upper end of the part L is attached a laterally extending arm M which is bent at m to increase its 35 elasticity and it is arched at m', the arched portion being perforated at m² to receive the pivot of a roller. The outer end of the arm M is riveted at m³ to a diagonally extending brace N which is attached as indicated to the 40 part L about midway between its upper and lower ends. The part L' may be provided with an eye l³ to receive the cord for lifting and lowering the bracket.

In Fig. 6 a simpler form of the invention 50 shown in Fig. 5 is illustrated. In this case there is a single vertical part O made of sheet metal and carrying anti-friction rollers o. The laterally projecting arm P is similar to the arm M shown in Fig. 5 except that it 55 is attached to the part O in a different way. In this case it will be observed that the arm P projects not from the edge of the part O but from the face thereof, the arm P being bent at right angles at p and riveted to the 60 face of the part O at its upper end. A diagonally arranged brace P' is attached to the outer end of the arm P and this brace is bent at right angles at p² and riveted to the lower portion of the part O. In this case the guide 65 D should be applied to the window frame in

such manner that it will hold the bracket in suitable position to support the roller outside the window frame. The bracket is provided with an eye p³ to which the lifting and lowering cord may be attached. In this form 70 of the invention no special means is provided for causing the bracket to automatically yield to accommodate variations in width of the window frame as this is not necessary, but the bracket possesses other 75 novel characteristics, such as the anti-friction rollers and the arched portion p⁴ perforated to receive the pivot of the roller.

In Fig. 7 the bracket comprises a vertical part Q to which is riveted another vertical 80 part Q'. The part Q is bent at q' so that it stands away from the part Q' in order to give it resiliency. A third part Q² is riveted to the part Q' and the part Q' is bent at q² to cause it to stand away from the part Q in 85 order that the part Q' may have a certain amount of resiliency. The vertical parts carry anti-friction rollers q adapted to slide in a suitable guide such as the guide D before mentioned. The upper portion of the part Q 90 is bent to form a roller-supporting bracket r which is perforated at r' to receive the pivot pin of a roller, and the upper end of the part Q' is likewise bent to form a bracket s perforated at s' to receive a pivot. The part 95 Q² may be provided with an eye s² to which may be attached a lifting and lowering cord.

Fig. 9 shows how a roller-supporting bracket of the kind shown in Figs. 1, 2 and 3 may be mounted in a suitable guide D and 100 support two shade rollers B, B'.

Fig. 8 shows another form of the invention. In this case 2 vertical parts T, T' are employed. These carry anti-friction rollers t. The part T is bent at t⁴ to give elasticity 105 to its upper portion and a bracket t² is formed by bending its upper end. This bracket is provided with a perforation t³ to receive the pivot of a roller. The part T' may be provided with an eye t' to receive a 110 lifting and lowering cord.

I claim as my invention:

1. The combination with a window frame of roller-supporting brackets constructed to yield to accommodate variations in width of the window frame in different horizontal planes and guides in which said brackets are adjustable vertically.

2. The combination with a window frame of vertical guides and brackets mounted to move in said guides, and provided with arms for supporting a roller which are adapted to yieldingly move toward and from the end of the roller.

3. The combination with a window frame of vertical guides secured thereto and roller-supporting brackets mounted to move in said guides, each comprising a vertical metal strip provided with anti-friction rollers and with a spring arm for supporting a shade 125 130

roller which yieldingly moves toward and from the roller and toward and from each other on the opposite sides of the roller.

4. A roller - supporting bracket, comprising a metal strip and a spring arm parallel with the strip and having one end attached thereto in combination with a guide in which said metal strip is vertically adjustable.

5. A roller - supporting bracket, comprising a metal strip provided with two roller-supporting spring arms, each of which has a part attached to the strip and an outer free portion for supporting a roller in combination with a vertically arranged guide in which said metal strip is vertically adjustable.

6. A roller - supporting bracket comprising a metal strip, spring arms projecting therefrom and laterally projecting roller-

supporting arms extending from said spring 20 arms.

7. A roller - supporting bracket, comprising a vertical part adapted to move in a guide and a laterally projecting arm bent to form an arch which is provided with a perforation to receive the pivot of a roller.

8. A roller - supporting bracket, comprising a vertical part adapted to move in a guide, anti-friction rollers carried thereby, a laterally projecting arm which is arched and 30 perforated to receive the pivot of a roller, and means for connecting the outer end of the arm with the vertical part of the bracket.

GUSTAVE RICHTER.
